INSULATING BAFFLE FOR REFRIGERATOR
EVAPORATORS

Homer E. Rosebrook, Greenville, Mich., assignor to Gibson Refrigerator Company, Greenville, Mich., a corporation of Michigan

Application January 17, 1951, Serial No. 206,337

3 Claims. (Cl. 62—10.3)

This invention relates to refrigerators, particularly those of the convection type.

Modern household refrigerators are usually cooled by means of an evaporator located adjacent the top thereof and maintained at a temperature considerably below freezing. Also, such evaporators are ordinarily provided with means for regulating the evaporator temperature within certain limits, so that on occasion the evaporator temperature may be lowered for quicker freezing water or foodstuffs within the evaporator.

The temperature maintained within the refrigerator storage compartment is dependent primarily upon the temperature of the evaporator, therefore when the evaporator temperature is lowered, the food storage compartment, particularly that portion close to the evaporator and below it, may become too cold and freeze articles not intended to be frozen.

The present invention avoids to a large extent the aforementioned disadvantage by providing a variable insulating baffle below the evaporator. The insulating effect is automatically variable to a degree, dependent upon the evaporator temperature. In general the invention comprises a baffle plate having a lower coefficient of heat transmission than the material composing the evaporator, located close enough to the evaporator to produce a sub-freezing temperature throughout the baffle plate. Thus, frost builds up on or melts off the baffle, depending upon the evaporator temperature, and as frost is an insulator, the insulating effect of the baffle varies.

In the drawings accompanying this application:

Figure 1 is a fragmentary front view of a refrigerator, with the door removed, showing the invention; and

Figure 2 is a fragmentary cross-sectional view taken on substantially the line 2—2 of Figure 1.

The invention is shown as embodied in a household refrigerator cabinet 10 of conventional construction. The refrigerator cabinet has a food storage compartment 11 therein, normally closed by a door, not shown.

In the upper part of the storage compartment is an evaporator 12 which extends substantially from side to side, and from front to rear of the compartment 11. The evaporator is preferably formed from metal having a high heat conductivity, such as aluminum or copper.

At each side of the evaporator are brackets 13 which support an insulating baffle plate 14 below the evaporator. The baffle plate 14 is preferably of glass or other material which has a lower coefficient of heat transmission than the material of the evaporator, but still will pass heat rather readily. The baffle plate 14 is of substantially the same horizontal extent as the evaporator and is located very close to the evaporator. For best results the lower surface of the baffle plate should be within one inch of the evaporator. The baffle plate 14 inclines slightly downwardly and rearwardly. The baffle plate is mounted on the brackets 13 so that it may be completely removed in hot summer weather, or for any other reason if the user so desires.

Attached to the rear wall of the cabinet is an auxiliary baffle 15 which inclines downwardly and forwardly beneath the rear edge of the baffle plate 14 and in close proximity thereto. The baffle 15 cooperates with the baffle plate 14 in restricting the flow of air within the refrigerator and deflects moisture running off of the inclined baffle plate 14 onto a drip pan 16 therebelow. The drip pan 16 is a combination storage shelf and drip pan supported below the baffle plate 14 by suitable supporting brackets 17. The shelf 16 is preferably imperforate, except for a small drain hole 18.

The shelf 16 is nearly as large as the cross-section of

the compartment 11. Consequently it too acts as a baffle to restrict the circulation of air within the compartment 11. Thus the space between the shelf 16 and baffle 14 is colder than the rest of the compartment below it, and may go below freezing if the evaporator temperature is set low enough. However, when the evaporator temperature is lowered the moisture in the air within the compartment condenses out and freezes on the baffle plate 14 rather rapidly, thus building up an insulating layer which reduces the transfer of heat to the evaporator and maintains a more uniform and higher temperature in the food storage compartment 11 than would otherwise be the case. When the temperature of the evaporator rises, some of the accumulated deposit of frost melts and drips from the baffle plate 14, reducing the insulating effect of the baffle.

From the foregoing it will be seen that the present invention provides a novel means of maintaining more uniform conditions in a refrigerator, regardless of changes in evaporator temperature, than would ordinarily be the case.

The scope of the invention is indicated in the appended claims.

1. A refrigerator cabinet having a food storage compartment therein, an evaporator in said compartment, a main baffle plate below said evaporator and spaced closely enough to said evaporator to substantially prevent movement of air therebetween, said main baffle plate being formed of material having a substantially lower coefficient of heat transfer than the material composing the evaporator and being of substantially the same horizontal extent as the evaporator, said main baffle plate being inclined downwardly toward a wall of said compartment, and a drip pan of substantially the same horizontal extent as the main baffle plate and spaced below said main baffle plate sufficiently to permit free flow of air between said main baffle plate and said drip pan.

2. A refrigerator cabinet having a food storage compartment therein, an evaporator in said compartment, a main baffle plate below said evaporator in closely spaced relation thereto, said main baffle plate being formed of material having a substantially lower coefficient of heat transfer than the material composing the evaporator and being of substantially the same horizontal extent as the evaporator, said main baffle plate being inclined downwardly toward a wall of said compartment, and a drip pan of substantially the same horizontal extent as the main baffle plate and spaced below the latter sufficiently to permit free flow of air between said main baffle plate and said drip pan, and an auxiliary baffle on said wall extending under the lower edge of said main baffle plate and over the corresponding edge of said drip pan.

3. A refrigerator cabinet having a food storage compartment therein, an evaporator in said compartment, the horizontal extent of said evaporator being substantially the same as that of the compartment, a main baffle plate below said evaporator, the lower surface of said main baffle plate being spaced not over one inch from said evaporator whereby to substantially prevent movement of air through the passages defined by the bottom of the evaporator and the main baffle plate, said main baffle plate being formed of material having a substantially lower coefficient of heat transfer than the material composing the evaporator and being of substantially the same horizontal extent as the evaporator, and a drip pan of substantially the same horizontal extent as the main baffle plate and spaced below said main baffle plate sufficiently to permit free flow of air between said main baffle plate and said drip pan.
